DESIGN FOR A CUFF LINK

Andrew Schwartz, Providence, R. I., assignor to Globe Jewelry and Chain Manufacturing Co.,
a corporation of Rhode Island

Application July 2, 1947, Serial No. 140,056

Term of patent 14 years

(Cl. D17—7)

To all whom it may concern:

Be it known that I, Andrew Schwartz, a citizen of the United States, residing at Providence, in the county of Providence and State of Rhode Island, have invented a new, original, and ornamental Design for a Cuff Link, of which the following is a specification, reference being had to the accompanying drawing, forming a part thereof.

Fig. 1 is a perspective view of a cuff link showing the new design;

Fig. 2 is a side view thereof; and

Fig. 3 is a top plan view thereof.

I claim:

The ornamental design for a cuff link, substantially as shown.

ANDREW SCHWARTZ.
